UNITED STATES PATENT OFFICE

GEORGE M. MURPHY, OF COLUMBUS, OHIO, ASSIGNOR TO THE BUCKEYE STEEL
CASTINGS COMPANY, OF COLUMBUS, OHIO

CAR COUPLING

Application filed April 5, 1928. Serial No. 267,611.

This invention relates to car couplers of the standard automatic type and has special reference to the means for transmitting a rotating motion to the rotary device for raising the lock and throwing the knuckle to its open position.

An object of the invention is to provide a simple and efficient uncoupling mechanism which may be readily installed, and adapted to work with the present uncoupling arrangement now employed on Pullman cars that are equipped with the standard "D" coupler, and to so construct the mechanism that it shall be also adaptable to all types of cars where the rotary method of operation of the coupler is used, and especially on cars used in passenger service where the coupler is required to be operated from both sides of car.

A further object is to so construct the mechanism that it will readily adapt itself to the forward and back movements of the coupler in pulling and buffing, and to provide special means for the wide lateral movement that is required for couplers in passenger service.

With these and other objects in view, the invention consists in certain novel features as hereinafter set forth and pointed out in the claims.

In the accompanying drawings:—

Figure 1 is a view in side elevation showing a coupler head having my improvements applied thereto, the supporting structure being shown in vertical section;

Figure 2 is a plan view of the same.

Figure 3 is a front elevation;

Figures 4, 5 and 6 are respectively a top plan, a front view and an end view showing the rotor with an arm and the eye in a vertical position.

Figures 7 and 8 are views of the main lever and the link connecting same to the eye on the arm of rotor.

The coupler head 1 is the usual standard head carrying a knuckle 2 and containing a lock 3 for securing the knuckle in closed position.

On the underside of the head, at the rear of the lock supporting portion thereof, is a depending bracket 4 in which is journaled

the rotor 5 carrying the lifter 6 which is connected to the lock by means of an intermediate link 7 whereby the lock is raised when a rotating motion is imparted to the rotor shaft.

According to the present invention, the rotor is provided at one end with an arm or crank 8 having an eye 9 in a vertical position at its free end, and a link 10 is hung in said eye.

Depending from the carrier iron 11 is a bracket 12 having forwardly diverging front faces and carried by the lower end of said bracket is a pin 13 upon which a lever 14 is mounted at its rear end for free pivotal movement.

The lever 14 is provided with an elongated eye 15 at its rear end which encircles the pin 13 between the walls of the bracket 12. By making the eye 15 elongated free movement of the lever 14 will be permitted when the coupler 1 is angled to its maximum position at either side of the carrier 11, the lever 14 being free to actuate the lock 3 when the coupler 1 is angled to either side.

The lever 14 is provided at its front end with a clevis 16 into which is hinged the connecting link 10, said link being free to rotate about a pin 17 of the clevis. The upper end of connecting link 10 is rotatably mounted in the eye 9 of the rotor arm 8 and is retained in this position by means of an upturned portion 10^a of link.

The construction of the rotor operating mechanism is such that the lever arm 8 is located to one side of the center line of coupler head 1. The lever 14 is in line with center of shank to provide more direct action on the rotor lever arm 8 and the relation of these two elements causes an offset to be made in the connecting link 10 as shown at 10^b. This would have a tendency to cause the lever 14 to shift to one side or the other when acted upon by an operating bail 18 through the medium of which motion is imparted to the lock lifting mechanism. To overcome the condition above mentioned, the forward portion of lever 14 is formed to provide a guide and support bar 19 on its underside, running parallel to the top member and spaced the proper distance to admit the oper-

ating bail 18. This guide bar is extended rearwardly and of sufficient length to provide a support for the bail 18, the weight of which acts to prevent the lock from jumping 5 up in the coupler head and permitting the knuckle to become accidentally unlocked when the train is run at high speed. The bail 18 may be supported by links 20 depending from the carrier iron 11 and it may be 10 provided with crank arms 21 with which actuating rods 22 cooperate, the latter being suitably mounted and intended to extend to the sides of the car where they may be conveniently manipulated without requiring the 15 operator to enter between the cars.

Having fully described my invention what I claim as new and desire to secure by Letters Patent, is:—

1. The combination with a coupler head, 20 a lock within the head, a rotor provided with a lever arm mounted on the underside of the head, said rotor being pivoted rearwardly of said lock, and connected with the lock to release the same for uncoupling, of a lever 25 mounted below and rearwardly of the rotor, a link between said lever and the lever arm on the rotor, means for swinging the lever upwardly, said lever having an elongated eye fulcrumed so that it may rock laterally on 30 its fulcrum and provided with a slot for engaging the last mentioned means.
2. The combination with a coupler head, a lock therein, and a rotor mounted on the underside of the head and connected with the 35 lock, of a lever having an elongated eye loosely fulcrumed below and at the rear of the rotor whereby it may rock laterally on its fulcrum and being provided with a slot for engaging the actuating means and connections between 40 the lever and the lever arm of the rotor.
3. The combination with a coupler head, a lock therein, and a rotor mounted below the head, said rotor being pivoted rearwardly of said lock, connections between said rotor 45 and said lock, and an arm on said rotor, a lever, a connection between said lever and said arm on the rotor, and operating means for said lever and acting downwardly to retain the lock in locked position.
4. The combination with a coupler head, a lock therein, and a rotor mounted on the underside of the head and connected with the lock, of a lever arm on the rotor, a lever, a link connecting said lever with the lever arm 55 of the rotor, an operating member, said lever having a guide bar and support for said operating member, and the operating member constituting weight means for holding the lock in locked position while train is in motion.
5. The combination with a coupler head, 60 its support and a lock within the head, of a rotor shaft provided with a lever arm having a vertically positioned eye at its free end, 65 a substantially vertical depending link sup-

ported by said arm, and a substantially horizontal lever connected to the car structure and attached to said link.

6. In a coupler of the Standard D type, a coupler head, a lock, a knuckle, a bottom-operated lock-lifting mechanism comprising a rotary uncoupling shaft having a connection with the bottom of the lock, a support on the under side of the coupler head forming a rotative bearing for the shaft, a member for actuating the uncoupling mechanism, and an intermediate lever connected at one end to an arm on the shaft at a point forwardly of said shaft and having a sliding engagement with said member, the said mechanism being disposed with reference to a car end sill so as to avoid interference with train service lines.

In testimony whereof, I have signed this specification.

GEO. M. MURPHY.
